UNITED STATES PATENT OFFICE.

EDNA M. NAKAZAWA, OF NEW YORK, N. Y.

BED.

1,266,039.

Specification of Letters Patent.

Patented May 14, 1918.

Application filed May 5, 1916. Serial No. 95,649.

To all whom it may concern:

Be it known that I, EDNA M. NAKAZAWA, a subject of the King of England, residing at New York, in the county of New York 5 and State of New York, have invented certain new and useful Improvements in Beds, of which the following is a specification.

My invention relates to a bed and more particularly to that class of beds known as 10 folding cots or cribs.

One object of the present invention resides in providing a bed of the character above mentioned which is constructed in such a manner that the mattress frame may be 15 folded in parallel relation with respect to the head and foot members, and the head and foot members collapsed with respect to each other or brought together so as to embrace therebetween the mattress frame when 20 the latter is in its folded position.

Another object resides in providing collapsible side members connecting the head and foot members and a member pivotally connected with either the head or the foot 25 member to limit the movement of the opposite member.

A further object resides in the novel manner of pivotally connecting the mattress frame and limiting member with either the 30 head or foot member in such a manner that they may be readily collapsed to form a compact package bed or may be opened out in a full size bed, in either case carrying the mattress.

35 With the above and other objects in view, I will now proceed to describe a specific embodiment of the present invention with particular reference to the accompanying drawings wherein I have illustrated such 40 embodiment and in which:

Figure 1 is a side elevation of a bed constructed in accordance with the present invention.

Fig. 2 is a sectional view on the line 2—2 45 of Fig. 1.

Fig. 3 is a sectional view of one side of the bed on the line 3—3 of Fig. 1.

Fig. 4 is a longitudinal section through the bed in the collapsed or folded position, 50 and

Fig. 5 is a sectional view on the line 5—5 of Fig. 4.

In detail:

The bed, as shown, comprises the head and 55 foot members designated respectively as A and B. The head member A comprises two

posts or uprights 1 and 2 each of which is slotted on the side as shown at 3 to accommodate the sliding pivots 4 of the U-shaped member C having its side members 5 and 6 60 connected by a base member 7 which serves to limit the movement of the foot member B when the member C is in the position shown in Fig. 1. The member C, when in the position shown in Fig. 1, is supported on flanges 65 8 carried by the posts of the head and foot members. By this construction, it will be apparent that when the head and foot members have been moved toward each other a prescribed amount, the member C may be 70 slightly raised and then rotated about its pivot points 4 to the position indicated in dotted lines at C' in Fig. 1, and when in this position the foot member B may be moved to the position indicated in dotted 75 lines at B' in Fig. 1. Opposite the slots 3 and on the inside of the posts 1 and 2 the slots 9 are provided which accommodate the pivots 10 carried by an extension 11 at right angles to the major portion of the mattress 80 frame 12. The said mattress frame 12 is provided at both ends with lugs or ears 13 for the purposes to be hereinafter set forth.

It will be seen that, by reason of the right angle extension 11 and its pivot, the mattress frame 12 may be swung upwardly or folded to a position parallel with the head and foot members A and B, as shown in Fig. 4, in which case it is embraced or inclosed between said head and foot members and 90 overlapped by the member C thus forming a very compactly packaged bed which may be opened out into a full sized bed when desired and the extension 11 is of sufficient length to provide for the accommodation of 95 a full size mattress since this construction leaves sufficient space between the head member A and the frame 12. In order to fasten the mattress to the frame and also the bed clothes if desired, as these may likewise be accommodated, I provide the said bed frame with eyelets 14 adjacent the foot end thereof and which are connected by an elastic member or other yieldable member 15 which is positioned, when the bed is made 100 up, as shown at 16.

The pivots 10, as will be readily seen, slide in the slots 9 and hence when the bed is opened out to the position 1 and 2, some means for supporting the mattress 110 frame must be provided. Therefore, the posts 1 and 2 of the head member A and

likewise the posts 1^a and 2^a of the foot member are provided with supporting brackets 16' which may be riveted or otherwise secured thereto and which are engaged by the lugs or ears 18 carried at the head and foot of the mattress frame 12. It is apparent that these lugs only engage the said members 16 when the mattress frame 12 is in the position shown in Figs. 1 and 2.

- 10 The bed herein described is primarily designed as a crib structure and to that end it is necessary to provide side members which will project above the mattress and prevent the occupant from falling out. To 15 this end the posts 1 and 2 of the head member and 1^a and 2^a of the foot member are slotted on their adjacent sides as shown at 17 and accommodate the blocks 18 which pivotally connect, as shown at 19, 20 with collapsible side members 20 which are constructed on the principle of lazy tongs having their central line of pivots indicated at 21. At the upper ends of the slots 17, ears 22 are located which may be engaged 25 by the notches 23 in the catch members 24 pivoted to the said posts at 25 and therefore after the bed has been opened out as shown in Figs. 1 and 2 and an occupant placed on the mattress D thereof, the extended side members 20 may be raised to 30 their highest position and the catch members 24 then engage with the lugs or ears 22 which project beneath the pivot points 19 and lie adjacent the members connecting the block 18 with the sides 20.

The operation of the bed will be readily ascertained from the foregoing description inasmuch as it is apparent that the head and foot members may be moved toward 40 each other to a collapsed position after the mattress frame 12 has been positioned in a plane parallel therewith and as said head and foot members move toward each other the lazy tong members 20 will also collapse 45 and when these members have been moved to the position shown in Fig. 4, the member C is then rotated about its pivot point

to inclose the sides, thus forming a compactly packed article of furniture.

While in the foregoing I have described 50 a specific embodiment of the present invention, it is, nevertheless, to be understood, that in practice I may resort to such modifications of the invention as fall within the scope of the appended claims. 55

I claim:

1. A bed including head and foot members, collapsible sides connecting such members, a mattress frame pivotally mounted on one of said members and arranged to fold 60 in a plane parallel therewith and unfold at right angles thereto and a U-shaped member having its sides pivotally connected with one of said members and arranged to fold in a plane parallel thereto and unfold at 65 right angles to said member to limit the separation of the head and foot members.

2. A bed including head and foot members, sides connecting such members, a mattress frame slidably and pivotally mounted 70 on one of said members and arranged to fold in a plane parallel therewith, and a U-shaped member pivoted to one of the first mentioned members and arranged to fold parallel with the latter and unfold at right 75 angles thereto to limit the separation of the head and foot members.

3. A bed including head and foot members, extensible sides connecting such members, a mattress frame carried by said head 80 member and arranged to fold parallel therewith and unfold at right angles, and a U-shaped member connected with said head member and arranged to fold parallel therewith and unfold at right angles to limit 85 the separation of the head and foot members.

In testimony whereof I affix my signature in presence of two witnesses.

EDNA M. NAKAZAWA.
